UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

INSULATOR-PIN-CENTERING MEANS

Application filed January 7, 1927. Serial No. 159,599.

The invention relates to insulators, particularly those of that type having a pin secured therein in axial relation thereto.

It is well known that in insulators of the suspension type the pin, which may be of any particular variety depending upon the character of the contemplated connection between successive units, is cemented within a recess or socket in the porcelain body. In some instances the wall of the socket or recess is sanded so as to insure proper holding action of the cement which fills the recess and which embeds the pin therein. It has been discovered that cement is flexible to a limited extent and is an important medium for the distribution of the loadings between the metal and porcelain parts of insulators. If the cement mass is too thin at any point or points concentrated loads result. In order to have a proper thickness of cement between the pin and wall of the socket or recess it has been proposed to make the pin hole of considerably larger diameter than the pin head, the space being of course filled with cement to embed the head. An objection to this has been that the pin may frequently be assembled in the insulator eccentrically of the pin hole, the result being that the mass of cement is too thick at some points and too thin at others, this consequently causing the bringing of unequal stresses and strains at different points instead of the entire load being uniformly distributed. It then becomes of importance to provide means whereby the pin may be comparatively accurately centered with respect to the recess or hole provided for its accommodation.

It is with the above facts in view that I have designed the present invention which has for its object the overcoming of this difficulty by the provision of means cooperating with the pin for centering it.

An important object is to provide centering means of this character which forms part of the insulator body itself instead of consisting of an auxiliary or extraneous device.

A more specific object is to provide centering means of this character which may consist simply of a recess or depression at the closed end of the pin hole, this depression be-

ing of substantially the same size as the pin head and of sufficient depth to accommodate the cushion ordinarily provided on the pin head regardless of whether the cushion be simply a coating of asphaltum or a paper, rubberoid or other suitable cushioning gasket.

An additional object is the provision of centering means of this character which will not add to the cost of production of the complete insulator and which will not involve any additional steps in the manufacture, the invention being consequently simple to carry out while greatly improving the efficiency of the insulator.

With the above and other objects and advantages in view, the invention preferably consists in the detailed structure to be herein-after more fully described and claimed, and illustrated in the accompanying drawing in which:

Figure 1 is a cross sectional view through an insulator of standard type showing it equipped with my invention and showing the pin in applied position.

Figure 2 is a similar view but showing the invention applied to an insulator in which the pin hole is grooved instead of sanded.

Referring more particularly to the drawing, and especially Figure 1, the numeral 1 designates, generally, the porcelain body of an insulator here disclosed as of the suspension type and including a skirt portion 2 from the center of which extends a stem 3 formed with a hole or socket 4 opening out at the underside of the insulator for the reception of the pin 5. The stem 3 is adapted to have secured thereto a cap, not shown, and the cap as well as the pin may be of the clevis, ball and socket or other type depending upon the particular form of connection desired for assembling a series of units to make a string or chain. In the drawing the insulator is of course shown in inverted position inasmuch as that is the proper position in which it is placed preparatory to the insertion of the pin within the socket or hole as is customary. Ordinarily, the wall of the socket or hole is sanded as indicated so as to provide means for insuring the proper gripping action of the cement 6 which embeds the pin

head 7 within the hole. The pin head is here disclosed as having two steps though it should be distinctly understood that it may have as few as one or as many more than two as desired, this detail being immaterial.

As mentioned above, it is desirable to provide an appreciable space between the pin and the wall of the hole or socket so that the mass of cement embedding the pin will have sufficient thickness to distribute the loads properly. To insure centering of the pin so that the space between it and the wall will be at least substantially uniform throughout, I provide a depression or recess 8 at the closed end of the hole or socket, this recess being of substantially the same diameter as the pin head so as to receive the same and consequently maintain the pin in coaxial relation to the insulator body. It is generally customary to provide a cushion at the end of the pin head and in some instances this cushion is simply a coating of asphaltum. However, the better practice is to equip the pin head with a disk 9 of paper, rubberoid or other suitable material, and in view of this practice it is intended that the recess or depression 8 be of sufficient depth to receive this cushion or gasket and to permit the end of the pin head also to enter. It might of course be possible to make the recess very shallow as it would still have its centering action upon the pin even though it received only the gasket or cushion for the reason that the cushion is secured to the pin head by a suitable adhesive and is incapable of movement with respect thereto.

In Figure 2 the same arrangement is disclosed except that the wall of the pin receiving socket or hole is not sanded but is provided with alternating ribs and grooves 10 and 11 respectively for insuring proper holding action of the cement. The recess is provided in exactly the same manner and performs the same function as in the first described form.

The pin is of course assembled with respect to the porcelain body in the usual manner it being, however, clear that it will be effectually centered so that its axis will coincide with that of the porcelain body, eccentricity and consequent development of unequal strains in service being eliminated. It is believed that the construction, operation and advantages will be readily apparent to one skilled in the art without further explanation.

While I have shown and described the preferred embodiments of the invention, it should of course be understood that there is no restriction as to the type of insulator or pin or any other limitations except in so far as defined by the claims hereunto appended.

Having thus described the invention, I claim:

1. In an insulator, a dielectric body having

a socket therein, and a pin having a head of less diameter than the socket adapted to be cemented within the socket, the dielectric body being formed with a recess at the end of the socket and communicating therewith, said recess having a flat wall and being of substantially the same diameter as the pin head and adapted to receive the same for centering the pin with respect to the dielectric body.

2. In an insulator, a dielectric body having a socket therein, and a pin having a head adapted to be cemented within the socket, the dielectric body being formed with a recess at the end of the socket and communicating therewith, said recess being of less diameter than the socket and of substantially the same diameter as the pin head and adapted to receive the same for centering the pin with respect to the dielectric body, the pin having a cushion fast on the end of its head, and said recess having a flat wall and being of a depth sufficient to accommodate at least the cushion.

In testimony whereof I affix my signature.

KENT A. HAWLEY.
